UNITED STATES PATENT OFFICE.

FRED C. OLIN, OF BUFFALO, NEW YORK, ASSIGNOR TO THE OLIN GAS ENGINE COMPANY, OF SAME PLACE.

GAS-ENGINE.

SPECIFICATION forming part of Letters Patent No. 613,390, dated November 1, 1898.

Application filed September 21, 1897. Serial No. 652,428. (No model.)

To all whom it may concern:

Be it known that I, FRED C. OLIN, a citizen of the United States, residing at Buffalo, in the county of Erie and State of New York, have 5 invented new and useful Improvements in Gas-Engines, of which the following is a specification.

This invention relates more especially to that class of gas-engines in which a working 10 stroke of the piston may be produced during every alternate forward movement of the piston.

The objects of this invention are to improve the construction of the valves and the 15 mechanism for operating the same, to provide a simple governor for regulating the speed of the engine, and to provide a reliable electric igniter for exploding the charges of fuel.

In the accompanying drawings, consisting 20 of three sheets, Figure 1 is a side elevation, partly in section, of my improved gas-engine. Fig. 2 is a top plan view of the same, partly in section. Figs. 3 and 4 are fragmentary horizontal sections, on an enlarged scale, in lines 3 3 and 4 4, Fig. 1, respectively. Fig. 25 5 is a vertical longitudinal section in line 5 5, Fig. 3. Figs. 6, 7, and 8 are vertical longitudinal sections, on an enlarged scale, in line 6 7, Fig. 2, showing different positions of the 30 governor mechanism. Fig. 9 is a vertical transverse section in line 9 9, Fig. 4. Figs. 10, 11, 12, and 13 are vertical sections in lines 10 10, 11 11, 12 12, and 13 13, Fig. 9, respectively. Fig. 14 is a fragmentary side 35 elevation of the igniter mechanism. Fig. 15 is a top plan view of the same. Fig. 16 is a vertical cross-section in line 16 16, Fig. 14.

Like letters of reference refer to like parts in the several figures.

40 A represents the base of the engine, provided at its rear end with bearings *a*; B, the shaft journaled in the bearings *a* and provided with the usual balance-wheels C; D, the working cylinder mounted on the front 45 end of the base; E, Fig. 2, the piston arranged in the cylinder, and F the connecting-rod which connects the piston with the crank *b* of the shaft B, all of which may be of any suitable and well-known construction.

40 G, Figs. 3 and 5, represents the valve-

chamber arranged on one side of the cylinder and connected by a port *g* with the front or firing end of the cylinder.

H represents an exhaust-chamber opening into the valve-chamber through the rear side 55 thereof and connected with an exhaust-pipe *h*.

I is an exhaust-valve arranged in the valve-chamber and having a movement toward and from a forwardly-facing exhaust-valve seat *i*, which is formed around the inlet end of the 60 exhaust-chamber. The exhaust-valve is mounted on the rear end of a longitudinally-reciprocating valve-rod *i'*, which is guided in a way *i''*, arranged on the rear portion of the exhaust-chamber. 65

J represents an air-chamber opening into the valve-chamber through the front side thereof and connected with an air-supply pipe *j*.

K is a fuel-chamber opening into the air-chamber and connected with a pipe *k*, which supplies the gas or other fuel. 70

L is a fuel-valve whereby the admission of fuel into the cylinder is controlled and which has a movement toward and from an inwardly-facing valve-seat *l*, which surrounds the outlet of the fuel-chamber. This valve is arranged on the rear or inner end of a longitudinally-reciprocating tubular valve-stem *l'*, which is arranged axially in line with and in 75 front of the exhaust-valve and which is guided in a way *l''*, formed in the front portion of the fuel-chamber. The fuel-valve is yieldingly held in a closed position by a spring *l''*, which surrounds the outer portion of the fuel-valve 80 stem and bears with its ends against the front side of the fuel-chamber and a collar *l'''*, arranged on the front end of the fuel-valve stem. 85

M represents an air-valve whereby the admission of air into the cylinder is controlled and which has a movement toward and from a rearwardly-facing valve-seat *m*, which surrounds the outlet of the air-chamber. This valve is arranged in rear of the fuel-valve and 90 is mounted on the rear end of a longitudinally-reciprocating tubular valve-stem *m'*, which is guided in the tubular stem of the fuel-valve. The connection between the air-valve and its stem is sufficiently loose to per- 95 100

mit the valve to rock slightly on the stem and adjust itself to its valve-seat and insure a perfect seating of this valve. For this purpose the rear end of the air-valve stem passes 5 loosely through a central opening in the air-valve and is provided with a rounded head or knuckle m^2 , which is held loosely in engagement with a central socket m^3 in the air-valve by a retaining screw-nut m^4 , engaging 10 with the air-valve in rear of the fuel-valve stem. The outer end of the air-valve stem is provided with a collar or screw-nut m^5 , which is arranged close to the front end of the fuel-valve stem and its collar l^1 .

15 During the normal operation of the engine the exhaust-valve is closed, as represented in Fig. 3, and the air and fuel valves are opened against the pressure of the spring l^3 by the suction of the piston while it makes its first 20 forward stroke, thereby drawing in a charge of air and fuel into the cylinder. During the subsequent backward stroke the air and fuel valves are closed, whereby the charge of air and fuel is compressed in the cylinder. At 25 the end of the backward compressing movement of the piston the charge is ignited, and the piston is propelled forward with a working stroke by the expansion of the gases, during which time the air, fuel, and exhaust valves 30 are closed. During the subsequent backward movement of the piston the exhaust-valve is opened, as represented in Fig. 5, and the spent gases are discharged. When the speed of the engine is above the normal, the exhaust-valve 35 is held open by the governor during the suction and compression strokes of the piston, whereby the piston draws air and spent gases backwardly through the exhaust and again expels the same instead of opening and drawing 40 in a fresh supply of air and fuel through the air and fuel valves and compressing the same.

It has been found in practice that it is impracticable to rigidly connect two valves to 45 the same stem and secure a perfect bearing of both valves against their seats. In the construction shown in the drawings a slight looseness or play is provided between the nut m^5 of the air-valve stem and the outer end of 50 the fuel-valve stem. This causes both valves to be moved toward their seats by the spring l^3 and the pressure of the gaseous mixture in the cylinder until the fuel-valve bears against its seat, after which the closing movement of 55 the air-valve is continued for a slight distance independent of the fuel-valve and is pressed against its seat by the pressure of the gases in the cylinder.

In order to positively prevent air and fuel 60 from being drawn into the cylinder during an idle suction stroke, an additional spring-pressure is applied to the air-valve when the exhaust-valve is open by the following means:

65 N represents a presser-rod moving lengthwise on the tubular air-valve stem and arranged with its inner end in the path of the exhaust-valve or its stem, while its outer end is

provided with a head n , which bears against the outer end of the air-valve stem. The presser-rod is yieldingly held in its rearmost 70 position by a spring n' , which bears with its ends against the front end of the presser-rod, and a cap n^2 , connected by a sleeve n^3 with the air-valve stem. During the normal suction stroke of the piston only the spring l^3 is compressed upon moving the air and fuel valves from the seats, and the spring n' is carried bodily with the valves, together with the presser-rod. When the exhaust-valve is 75 opened, it engages with the presser-rod and moves the same forwardly slightly, as represented in Fig. 5, thereby adding the resistance of the spring n' to that of the spring l^3 for holding the air-valve shut. If the piston is making a suction stroke while the exhaust-valve is open and abuts against the rear end of the presser-rod, the piston cannot suck the air-valve from its seat, owing to the combined resistance of the springs n' and l^3 , which is 80 strong enough for this purpose, thereby preventing the piston from drawing into the cylinder a charge of air and fuel.

The mechanism whereby the exhaust-valve is operated is constructed as follows:

O, Figs. 1, 2, 3, and 5, represents a spring 95 whereby the exhaust-valve is yieldingly held in its rearmost or closed position and which bears with its ends against the rear side of the exhaust-chamber and a collar o' on the exhaust-valve stem.

P, Figs. 1, 2, 4, 6, 7, and 8, represents an abutment-head arranged on the rear end of the exhaust-valve stem and provided on its upper side with a rearwardly-facing shoulder p .

Q represents a longitudinally-reciprocating thrust-bar whereby the exhaust-valve is opened and which is provided at its front end with a bearing-piece q , which is adapted to bear against the shoulder p of the abutment-head. The rear end of the thrust-bar is provided with an eccentric-strap which surrounds an eccentric q' on the shaft, whereby a forward-and-backward movement is imparted to the thrust-bar during each rotation 110 of the shaft. The piston in the working cylinder and the thrust-bar move longitudinally together, and during this movement the thrust-bar is alternately lowered with its bearing-piece into line and raised out of line with 115 the shoulder of the abutment-head. During the return movement or compression stroke of the piston the thrust-bar is raised, as represented in Fig. 8, so that its bearing-piece does not engage with the abutment-head and 120 open the exhaust, while the thrust-bar moves toward the front of the engine, together with the piston. During the next return movement or exhaust stroke of the piston the thrust-bar moving in the same direction is 125 lowered, as represented in Fig. 7, so that its bearing-piece is arranged in line with and engages with the shoulder of the abutment-head, thereby opening the exhaust-valve and

130

permitting the products of combustion to escape from the cylinder.

R, Figs. 4, 9, 12, and 13, is a rotary cam which engages with the under side of a lateral extension r on the inner side of the thrust-bar and whereby the thrust-bar is raised out of line with the shoulder of the abutment-head during every alternate forward movement thereof. This cam is substantially square, having four flat sides forming four salient or cam portions r' , and is journaled on a transverse arbor r^2 , which is secured with its inner end to a stationary part of the engine.

r^3 , Fig. 13, is a ratchet-wheel secured to the rotary cam and having eight teeth, and r^4 is a pawl pivoted on the thrust-bar and held with its hook in engagement with the teeth of the ratchet-wheel by a spring R' , secured to the thrust-bar. During each rearward stroke of the thrust-bar its pawl turns the ratchet-wheel and the cam connected therewith one-eighth of a rotation, whereby the high and low portions of the cam are successively presented to the thrust-bar and the front end of the latter is alternately raised and lowered preparatory to beginning a forward stroke.

In order to avoid hammering and jarring of the engine when the bearing-piece of the thrust-bar engages with the abutment-head, the latter is yieldingly connected with the exhaust-valve stem, so as to cushion these parts when they come together. For this purpose the abutment-head is permitted to move lengthwise on the valve-rod to a limited extent by a pin or screw p' secured to the rod and engaging with a longitudinal slot p^2 in the abutment-head. The head is yieldingly held in its rearmost position with the front end of its slot in engagement with the stop-pin p' by a spring p^3 , bearing with its ends against the head and the collar o' on the rod. The spring p^3 is stiffer than the spring o , so that the abutment-head and exhaust-valve rod are practically rigid with reference to each other, except when the head is struck by the bearing-piece of the thrust-bar. The abutment-head is guided in its longitudinal movements by a guide-arm p^4 , which projects inwardly from the abutment-head into engagement with a longitudinal slot p^5 in a bracket p^6 , the latter being secured to the cylinder, as shown in the drawings, or some other stationary part of the engine.

r^5 is a sleeve which is secured to the arbor outside of the rotary cam and provided at its inner and outer ends with heads or disks r^6 r^7 , one of which is formed integrally with the sleeve, while the other has a screw connection with the sleeve. The outer disk of the sleeve preferably bears against the outer side of the thrust-bar and the inner disk engages with a longitudinal slot r^8 in the thrust-bar, thereby serving as guides for the latter during the longitudinal and vertical movements thereof.

The mechanism whereby the speed of the engine is regulated is constructed as follows:

S, Figs. 4, 6, 7, and 8, is a vertically-swinging detent latch or pawl whereby the exhaust-valve is held open during the suction and compression strokes of the piston when the engine is running above the normal speed, thereby preventing a charge of fuel from being drawn into the cylinder. This pawl is pivoted at its rear end on the sleeve r^5 and its front end is adapted to be raised or lowered into an operative or inoperative position.

s is a rearwardly-facing shoulder formed on the rear end of the abutment-head below the upper shoulder p , and s' is a recess also formed in the rear end of the head below the lower shoulder. During the first portion of the forward movement of the abutment-head with the exhaust-valve and its stem the front end of the detent-latch engages with said recess and during the last portion of the forward movement of the head its lower shoulder is carried slightly forward of the latch and the latter is lifted quickly, so that its front end stands behind the lower shoulder. The latch is yieldingly held in a depressed position by a spring s^2 , secured to the rear end of the abutment-head and bearing against the upper side of the latch.

T, Figs. 1, 2, 4, 9, 10, and 11, represents an oscillating lifting-disk whereby the latch is raised and which is journaled on the arbor adjacent to the outer side of the guide-disk r^7 . This disk is provided on its front portion with an inwardly-projecting lifting finger or pin t , which engages with the under side of the latch. The lifting-disk is normally turned backward in the direction of the arrows, Figs. 10 and 11, for lowering its front pin t and the latch resting thereon by a spring t^2 , which is fastened at one end to the lifting-disk and with its other end to an adjusting-plate t^2 . The latter bears with its inner side against a shoulder t^3 on the arbor adjacent to the outer side of the lifting-disk and is held in its adjusted position by a clamping screw-nut T' , engaging with the screw-threaded outer end of the arbor and bearing against the outer side of the plate. The backward movement of the lifting-disk is limited by a stop t^4 , which is formed on the outer guide-disk r^7 below the lifting-finger and against which the latter is adapted to engage.

t^5 is a flat-sided trip-finger projecting inwardly from the lower portion of the lifting-disk, and t^6 is a depending tappet which is secured to the under side of the thrust-bar and which is adapted to engage with the rear side of the trip-pin and turn the same forwardly, together with the lifting-disk, for lifting the latch. The relative position of the trip-finger and the tappet is such that when the thrust-bar is elevated and moves forwardly with an idle stroke during the compression stroke of the piston the tappet is raised above the trip-finger, so that it does not strike the latter as the tappet moves forward with the thrust-

bar, as represented in Fig. 8. When the thrust-bar moves forward in a lowered position with its bearing-piece in engagement with the abutment-head for opening the exhaust-valve, the tappet is lowered in line with the trip-finger, and during the last portion of the forward movement of the thrust-bar the tappet engages with the trip-finger and turns the same forwardly in the direction of the arrow, Fig. 7, whereby the lifting-disk is turned forwardly, and its lifting-finger raises the latch, so that its front end stands behind the lower shoulder of the abutment-head.

- 15 When the engine is running at a normal speed, the momentum of the lifting-disk as it is turned by the tappet is such that the front end of the latch is carried only a short distance upwardly in rear of the lower shoulder, 20 which enables the latch to drop quick enough to clear the lower shoulder before the latter strikes the latch during the first portion of the backward movement of the abutment-head, thereby permitting the exhaust-valve 25 to move backward with the thrust-bar and close. If the engine is running above the normal speed, the tappet turns the lifting-disk forwardly with greater force and the latter, owing to its increased momentum, is turned 30 farther, whereby the front end of the latch is raised higher in rear of the lower shoulder of the abutment. This increase in the distance which the latch is raised when the engine is running above normal speed is so determined 35 that the latch cannot drop sufficiently rapid to clear the lower shoulder of the abutment during the first portion of the backward movement of the latter, which causes this shoulder to strike the front end of the latch and retain 40 the latter in an elevated position, whereby the abutment is prevented from moving backward with the thrust-bar and the exhaust-valve is held open during the subsequent suction and compression strokes of the piston. 45 During the last portion of the second following forward stroke of the thrust-bar in a lowered position the abutment is again released from the latch and the latter is permitted to clear the lower shoulder if the speed of the 50 engine has dropped below the normal, thereby permitting the abutment-head to follow the thrust-bar during the subsequent backward movement of the latter, whereby the exhaust-valve is closed.

55 By adjusting the plate t^2 on the arbor the tension of the spring t' may be regulated for adjusting the governor.

The mechanism whereby the charges of fuel in the cylinder are ignited is constructed as 60 follows:

V, Fig. 3, represents an igniting-chamber, which opens into any convenient portion of the space which contains the charge of fuel, this igniting-chamber, as shown in the drawings, being connected with the valve-chamber.

u u' represent the stationary and movable

contacts of an electric igniter, which are arranged in the igniting-chamber, the former being supported in the chamber by an insulating-plug and the latter being mounted on a longitudinally-reciprocating rod u^2 , which is guided in the igniting-chamber.

V' represents an electric generator having its poles connected with the electric contacts.

W, Figs. 1, 14, 15, and 16, represents a vertical rock-lever arranged adjacent to the inner side of the thrust-bar or other reciprocating part of the engine and pivoted on a stud w . The latter is arranged transversely above the thrust-bar and is secured with its inner end to a standard w' , arranged on the base. The lower arm of the rock-lever is connected with the rear end of the rod which carries the movable contact, and the upper arm of the rock-lever is provided with a horizontal finger w^2 , which is arranged transversely over the thrust-bar. The rod u^2 is yieldingly held in its rearward position for separating the contacts and for turning the rock-lever backwardly in the direction of the arrow, Fig. 14, 90 by a spring w^3 , which bears with its ends against the igniting-chamber and a collar on the igniter-rod u^2 .

x represents a rearwardly-inclined spring-catch which is adapted to couple the thrust-bar and rock-lever. This catch is secured with its rear end to the upper side of the thrust-bar and is provided at its front end with a hook having an inclined front side x' and an abrupt rear side x^2 .

y is a releasing-arm whereby the catch is disengaged from the rock-lever. This arm is mounted with its lower end on the stud w , outside of the rock-lever, and bears with its inner side against a shoulder y' on the stud. The upper end of the releasing-arm is provided with a roller or pin y^2 , which overhangs the inclined portion of the catch. During the forward movement of the thrust-bar the inclined side of the hook on the catch engages 110 with the finger of the rock-lever and is deflected downwardly until the hook has passed the finger, when the catch rises and its hook is carried upwardly in front of the finger. During the initial portion of the subsequent 115 rearward movement of the thrust-bar the abrupt side of the hook engages with the finger of the rock-lever and turns the latter forwardly in a direction opposite to that indicated by the arrow, Fig. 14, whereby the movable 120 contact is engaged with the stationary contact and the electric circuit is closed. During the next portion of the backward movement of the thrust-bar the hook of the catch is disengaged from the finger of the rock-lever by reason of the inclined portion of the catch engaging with the roller of the releasing-arm, whereby the rock-arm is liberated and quickly returned by the spring w^3 to its 125 normal position, together with the rod u^2 , thereby separating the contacts and forming a spark which ignites the charge of fuel.

u u' represent the stationary and movable

The time at which the ignition of the charge of fuel takes place is regulated by raising or lowering the roller y^2 , which is done by turning the releasing-arm of the stud. The releasing-arm is held in its adjusted position by a clamping screw-nut y^3 , which engages with the screw-threaded outer end of the stud and bears against the outer side of the releasing-arm.

10 I claim as my invention—

1. In a gas-engine, the combination with the air-chamber and the fuel-chamber opening into the air-chamber, of an inwardly-opening fuel-valve adapted to close the outlet of the fuel-chamber and provided with an outwardly-facing shoulder and an inwardly-opening air-valve adapted to close the outlet of the air-chamber and provided with an inwardly-facing shoulder adapted to be engaged by the shoulder of the fuel-valve, substantially as set forth.

2. In a gas-engine, the combination with the valve-chamber, the exhaust-chamber and air-chamber opening into opposite sides of the valve-chamber, and the fuel-chamber opening into the air-chamber, of an inwardly-opening fuel-valve adapted to close the outlet of the fuel-chamber and provided with a tubular valve-stem, a spring bearing against a shoulder on the fuel-valve stem, an inwardly-opening air-valve adapted to close the outlet of the air-chamber and provided with a valve-stem which is arranged in the tubular stem and which is provided with a shoulder bearing against the tubular stem, and an inwardly-opening exhaust-valve adapted to close the exhaust, substantially as set forth.

3. In a gas-engine, the combination with the valve-chamber provided with an inlet and an exhaust, of an inwardly-opening inlet-valve adapted to close said inlet and provided with a stem, a separate presser-rod guided on said stem, a spring interposed between said stem and rod, and an inwardly-opening exhaust-valve adapted to close said exhaust and to bear against said rod when the exhaust-valve is opened, substantially as set forth.

4. In a gas-engine, the combination with the valve-chamber, the exhaust-chamber and air-chamber opening into opposite sides of the valve-chamber, and the fuel-chamber opening into the air-chamber, of an inwardly-opening fuel-valve adapted to close the outlet of the fuel-chamber and provided with a tubular valve-stem, a spring bearing against a shoulder, on the fuel-valve stem, an inwardly-opening air-valve adapted to close the outlet of the air-chamber, a tubular valve-stem guided in the fuel-valve stem and connected at its inner end with the air-valve while its outer end is provided with a shoulder bearing against the fuel-valve stem, a presser-rod guided in the air-valve stem, a spring interposed between the outer ends of the presser-rod and the air-valve stem, and

an inwardly-opening exhaust-valve adapted to close said exhaust and to bear against said rod when the exhaust-valve is opened, substantially as set forth.

70

5. In a gas-engine, the combination with an exhaust-valve connected with an abutment, of a reciprocating thrust-bar adapted to engage with said abutment for opening the exhaust-valve, a rotary cam mounted on a stationary support and having alternate salient and receding portions adapted to engage with the thrust-bar, a ratchet-wheel arranged on the cam, and a pawl arranged on the thrust-bar and engaging with the ratchet-wheel for turning the same and the cam one space during each backward movement of the thrust-bar, whereby the salient and receding portions of the cam are successively engaged with the thrust-bar and the latter is shifted regularly into line and out of line with said abutment, substantially as set forth.

6. In a gas-engine the combination with the exhaust-valve connected with an abutment and a reciprocating thrust-bar adapted to engage with said abutment for opening the exhaust-valve, of a separate movable latch which is mounted on a stationary support and which is adapted to engage with said abutment and hold the exhaust-valve open when the speed of the engine is above the normal, and a shifting mechanism which is operated by the thrust-bar and whereby the latch may be shifted into the path of the abutment during each forward stroke of the thrust-bar, substantially as set forth.

7. In a gas-engine, the combination with the exhaust-valve connected with an abutment, and a reciprocating thrust-bar adapted to engage with said abutment for opening the exhaust-valve, of a separate movable latch mounted on a stationary support and adapted to be moved into and out of the path of the abutment, an oscillating lifting-disk provided with a finger engaging with said latch, and a tappet arranged on the thrust-bar and adapted to turn the disk for lifting the latch, substantially as set forth.

8. In a gas-engine, the combination with the exhaust-valve connected with an abutment, and a reciprocating thrust-bar adapted to engage with said abutment for opening the exhaust-valve, of a movable latch adapted to be lifted into the path of the abutment, an oscillating lifting-disk provided with a finger engaging with said latch, a spring whereby the disk is turned backwardly, a stop whereby the backward movement of the disk is limited, and a tappet arranged on the thrust-bar and adapted to turn the disk forwardly, substantially as set forth.

9. In a gas-engine, the combination with the exhaust-valve connected with an abutment, of a longitudinally-reciprocating thrust-bar adapted to engage with said abutment for opening the exhaust-valve, mechanism whereby the thrust-bar is alternately moved into

line and out of line with the abutment, a pivoted latch adapted to be lifted into the path of the abutment, an oscillating lifting-disk provided with a pin which engages with said latch, a spring whereby the disk is turned backwardly, a trip-pin arranged on the disk, and a tappet arranged on the thrust-bar and adapted to engage with the trip-pin when the thrust-bar engages with the abutment and to

clear the trip-pin when the thrust-bar clears the abutment, substantially as set forth.

Witness my hand this 3d day of September, 1897.
